THERMOSTATIC CIRCUIT INTERRUPTER

Paul R. Lee, Mansfield, Ohio, assignor to Westinghouse Electric & Manufacturing Company, East Pittsburgh, Pa., a corporation of Pennsylvania

Application August 3, 1938, Serial No. 222,796

9 Claims. (Cl. 200—138)

My invention relates to circuit interrupters and more particularly to a wide differential creep-type thermostat.

The contacts of present creep-type thermostats, or those having a slow make and break, have an exceedingly small separation therebetween which is of the order of .001 inch or less, resulting in a fluttering action during such make or break and, therefore, producing an undesirable amount of radio-interfering impulses, as well as serious damage to the contacts. Accordingly, the use of creep-type thermostats has been somewhat limited and retarded, especially in domestic appliances, such as roasters, waffle irons and the like.

It is, therefore, an object of my invention to provide a creep-type thermostat suitable for domestic appliances, or the like, and free of any radio-interfering impulses by reason of being void of any fluttering action and having an increased contact separation.

A further object of my invention is to provide a creep-type thermostat having an appreciable operating differential and a positive contact pressure.

Another object of my invention is to provide a creep-type thermostat including two cooperating bimetallic members, one of which is adapted to produce an increased contact separation and a positive contact pressure.

A further object of my invention is to provide a creep-type thermostat including two cooperating bimetallic members adapted to flex in opposite directions, for producing an increased contact separation and a positive contact pressure.

Another object of my invention is to provide a creep-type thermostat including two cooperating bimetallic members, with one of the members mounted upon the other member and adapted to bodily move therewith and to flex in an opposite direction with a given change in temperature.

A further object of my invention is to provide an inexpensive, rugged, manually adjustable creep-type thermostat capable of operating without contact-fluttering.

A still further object of my invention is to provide a creep-type thermostat capable of operating without contact-fluttering due to vibration.

Other objects of my invention will either be pointed out specifically in the course of the following description of a device embodying my invention, or will be apparent from such description.

In the accompanying drawings:

Figure 1 is a top plan view of a device embodying my invention;

Figs. 2, 3 and 4 are sectional views taken along the line II—II of Fig. 1 showing the device in its various operating positions;

Fig. 5 is a top plan view of a modified form of the device embodying my invention;

Fig. 6 is a side elevational view of the device shown in Fig. 5; and

5 Figs. 7, 8 and 9 are end views of the device shown in Fig. 5, illustrating its various operating positions.

Referring to Figures 1 to 4, inclusive, I show a thermostat or circuit interrupter 10 comprising 10 a supporting base or structure 12, a mounting frame 14, preferably formed of insulating material, flexibly attached to the base 12 by a resilient member 16, a main bimetallic member 18 insulatedly attached at one end thereof to the structure 12, a second bimetallic member 20 attached to the mounting frame 14 and operatively associated with the main bimetallic member 18, a plurality of adjusting members or screws 24 and 26 operatively associated with the frame and the second bimetallic member 20 for adjusting and varying the operation of the cooperating contacts 28 and 30, and another adjusting screw 22 operatively associated with the base 12 and the resilient member 16.

25 Generally speaking, and as hereinafter described in detail, the operation of the thermostat, after being operatively associated or connected to a circuit (not shown) by means of terminals 32 and 34, respectively associated with 30 resilient member 16 and main thermostatic member 18, is substantially as follows: The circuit through the thermostat 10 extends from terminal 32 through resilient member 16, second bimetallic member 20, contacts 30 and 28, and through the main bimetallic member 18 to the second terminal 34. Passage of current through the main bimetallic member 18 causes it to heat and flex downwardly substantially as shown by the arrow A (Fig. 2). In a similar manner, the second bimetallic member 20 flexes downwardly with an increased temperature thereof and biases the contact 30 against contact 28. Inasmuch as the ohmic resistance of the second bimetallic member 20 is considerably greater than that of the main bimetallic member 18, the second bimetallic member will heat faster than the first member, with a given value of load current. This ability of the second member 20 to change its temperature faster than the first member 18 will cause the

40 second bimetallic member 20 to flex downwardly a greater amount than that of the main bimetallic member 18 as such members increase in temperature, causing the second member 20 to carry the free end of the first member 18 downwardly, substantially as hereinafter described. The downward biasing action and movement of the second bimetallic member 20 ensures a positive contact pressure between the contacts 28 and 30, as hereinafter set forth.

45 50 55 60 The downward movement of the second mem-

ber 20 is limited by the adjusting screw 26. Accordingly, as the main bimetallic member 18 continues to increase in temperature it continues to flex downwardly, separating the contact 28 from the contact 30. The second bimetallic member 20 will, upon separation of the contacts and the interruption of current passing through the bimetallic members, cool more rapidly than the first member 18, whereupon such member will quickly straighten out and move upwardly towards the contact adjusting screw 24, resulting in an increased contact separation upon the disengagement of the contacts by means of the first member. The first bimetallic member 18 will then be required to flex upwardly, upon cooling, a substantial distance before engaging the contact 30 and reenergizing the circuit.

More specifically, the supporting structure or base 12, in this instance, comprises an upper flat member 36 and a depending end portion 38. It is preferred that these portions be formed of an insulating material, such as a phenolic resin, or the like. Moreover, it is to be understood that such structure may be formed of any other suitable material. Although members 36 and 38 may be integral, if desired, a separate upper plate portion 36 is preferably rigidly attached to the depending portion 38 by means of suitable rivets 40. The adjusting screw 22 is threadedly inserted through the top plate portion 36 of the structure 12 to cooperate with and operatively adjust the relative position of resilient member 16 and mounting frame 14, as hereinafter described. If desired, the adjusting screw 22 may have an insulating button 23 located on its lower end to adequately insulate it from the resilient member 16.

The mounting frame 14 is, in this instance, formed of an insulating material, such as a phenolic resin, or the like, into substantially a J-shaped member flexibly attached to depending member 38 of the supporting structure 12 by means of resilient member 16. The J-shaped mounting frame 14 has a plurality of threaded apertures 23 and 25 located therein, one on top and one in the bottom extension of such frame. The adjusting screws 24 and 26 are then operatively associated with the threaded apertures 23 and 25 to adjustably limit the movements of the second bimetallic member 20, substantially as hereinafter described.

The member 14 is rigidly attached at one end thereof to the resilient member 16, in this instance, by means of a suitable rivet 42. The second end of the resilient member 16 is rigidly attached to the depending portion 38 of the supporting structure 12. The resilient member 16 is positioned upon the depending portion 38 in such a manner that the adjusting screw 22, operatively associated with the supporting base or structure 12, operatively engages such resilient member. It, therefore, follows that the adjusting screw 22, through its cooperation with the resilient member 16, may readily adjust the relative position of the mounting frame 14 with respect to the base or structure 12.

The main bimetallic member 18 is, in this instance, a strip-type bimetallic member rigidly attached at one end to the lower face of depending portion 38 of supporting structure 12, preferably by rivets 40, and having contact 28 rigidly attached at its free end. The main bimetallic member 18 is constructed in such a manner and positioned upon the supporting base 12 in such a way that it will flex downwardly with an in-

creased temperature thereof. It is, therefore, obvious that inasmuch as the main bimetallic member 18 is rigidly attached to the supporting structure 12 such bimetallic member will flex a given amount with respect to such supporting structure for given temperature changes of such bimetallic member. Such temperature changes may be due to the changes in the ambient or due to the passage of current through member 18, or both.

10 The second bimetallic member 20 is, in this instance, a three-legged snap-acting bimetallic member rigidly attached at one end thereof to the mounting frame 14, adjacent one end of resilient member 16, by means of rivet 42. The second member 20 has rigidly attached near its free end the second contact 30, which is operatively associated with the first contact 28, attached to the main bimetallic member 18.

15 In addition, member 20 has a considerably higher ohmic resistance and is lighter in mass than member 18, whereby member 20 will heat faster and cool quicker than member 18. Further it is to be understood that the second bimetallic member 20 may be a snap-acting member as herein described or may be a fast-moving strip-type bimetallic member or any other suitable thermal responsive bimetallic device which will heat and cool faster than the first bimetallic member 18.

20 Inasmuch as the second bimetallic member 20 is substantially smaller in mass than the first bimetallic member 18, as is obvious, and has a greater ohmic resistance than such first member, the common current passing through the thermostat will then cause the second bimetallic member 20 to change or increase its temperature at a greater rate than the first bimetallic member 18, and to produce a greater downward biasing action than the first bimetallic member. Accordingly, it is obvious that with the passage of current through the thermostat the second bimetallic member 20 will bias the first bimetallic member 18 downwardly, regardless of the direction of biasing action of the first member, causing such members to be moved downwardly with a continued passage of current therethrough. However, the downward movement of the bimetallic member 20 is limited by the engagement of the free end of such member 20 with the adjusting screw 26.

25 It is obvious, therefore, that the downward biasing action of the second bimetallic member 20, which is substantially greater than the downward or upward biasing action of the first bimetallic member 18, whether the first member 20 be heating or cooling, respectively, results in a good contact between the contacts 28 and 30, and ensures a positive contact pressure therebetween during the engagement thereof between the operating limits of the second bimetallic member as determined by the adjusting screws 24 and 26.

30 It, therefore, follows that for the contacts 30 and 28 to become separated, the main bimetallic member 18 must continue its downward movement in response to an increased temperature. As the main member 18 increases in temperature, it will flex downwardly, causing the contact 28 to be separated from contact 30 substantially as shown in FIG. 3. Inasmuch as the passage of current through the second bimetallic member 20 is then discontinued, and inasmuch as the mass of the second member 20 is considerably less than that of the first member 18, the second member will rapidly cool at a rate greater

than that of the main bimetallic member 18. As the second bimetallic member 20 cools, it will flex upwardly, say with a snap action, being restrained by the adjusting screw 24, substantially as shown in Fig. 4. The first bimetallic member 18 will then be required to travel an additional distance, namely, that distance the contact 30 travels between adjusting screws 28 and 24, before contact 28 can become reengaged with contact 30. However, with the passage of time, and as the main bimetallic member 18 cools, such member will flex upwardly, permitting the contact 28 to be reengaged with contact 30, which in turn permits current to pass therethrough, substantially as hereinabove described.

It is, therefore, obvious that the main bimetallic member 18 is adapted to disengage and reengage the contacts 28 and 30 in response to predetermined temperature conditions, and that the second bimetallic member 20, operatively associated therewith, is adapted to separate the contacts 30 and 28 an additional distance after disengagement, and also ensures a positive contact pressure between the contacts during engagement thereof.

The adjusting screw 24 cooperates with the second bimetallic member 20 by limiting its upward movement. In addition, the adjusting screw 24 prevents the main-bimetallic member 18 from applying an excessive strain on the second bimetallic member 20, such as when the mounting frame 14 and second member 20 have been moved toward the first member 18, in response to the movements of the adjusting screw 22, as hereinafter described.

The manually operable adjusting screw 22, operatively associated with the supporting structure portion 36 and the resilient member 16, is adapted through the cooperative action of resilient member 16, to bodily move the mounting frame 14 either away from or towards the main bimetallic member 18. When the adjusting screw 22 is rotated so as to force the mounting frame 14 downwardly or towards the bimetallic member 18, it is obvious that the contact 30, mounted on the second bimetallic member 20, will likewise be moved towards the main bimetallic member 18, and therefore, it follows that the main bimetallic member will disengage the contacts 28 and 30 at a temperature above that which would cause separation of the contacts if the mounting frame was left in its original position. It is also apparent that the adjusting screw 22 may be rotated substantially counter-clockwise such a distance that the mounting frame 14 will be backed away from the main bimetallic member 18 such a distance that it would be impossible for the bimetallic member 18 to contact the second bimetallic member 20 or to reengage the contacts 28 and 30. With the thermostat operable in such ways, it is obvious that such thermostat will function not only as a manually adjustable thermally operable circuit interrupter, but also as a manually operable switch.

When it is desired to employ the thermostatic circuit interrupter 10 embodying my invention, such thermostat is operatively associated, through terminals 32 and 34, with the circuit (not shown) it is desired to control. In addition, the thermostat may be located in juxtaposition with an electrical heat-emitting device (not shown) that is controlled by the thermostat, permitting the temperature variations thereof to aid in the operation of such thermostat. The adjusting screw 22 is then adjusted to a predetermined position

to bodily move the mounting frame 14 and second bimetallic member 20, as hereinabove described, to cooperate with the main bimetallic member 18 in a manner already set forth.

With the thermostat connected to the circuit to be controlled (not shown), and assuming the bimetallic members to be cold, such bimetallic members will be located in an upper position (Fig. 2) and the current will pass therethrough, as hereinabove described. The second bimetallic member 20 will then cause the two members to be moved downwardly a predetermined distance depending upon the setting of adjusting screw 24. The main bimetallic member 18 will then continue its travel with an increase in temperature, disengaging the contacts 28 and 30 at a predetermined temperature value (Fig. 3). The second bimetallic member 20 will then cool off and relatively quickly return to its upper position, as determined by the adjusting screw 24, resulting in a wide gap between the contacts 30 and 28 (Fig. 4). The circuit will thus be opened, permitting the controlled device (not shown) to decrease in temperature simultaneously with the main bimetallic member 18. As such member cools, it will flex upwardly, reengaging the contacts 28 and 30 and reconnecting the controlled device in circuit, permitting the thermostat 10 to again operate in a similar cycle.

Referring to Figs. 5 to 9, inclusive, I show a modified form of device embodying my invention comprising a J-shaped supporting structure 52, a main bimetallic member 54 flexibly attached to the supporting structure 52 by means of a U-shaped resilient member 56, and a second bimetallic member 58 insulatedly attached to the free end of the main bimetallic member 54 and extending transversely thereof. Suitable terminals 60 are positioned near one end of supporting structure 52 and are respectively secured to spaced stationary contacts 62 by means of a suitable rivet 74. Movable contacts 64 are rigidly attached near the ends of the second bimetallic member 58 to cooperate with stationary contacts 62.

The supporting structure 52 is, in this instance, formed into a substantially J-shaped configuration from a single sheet of metal. However, it is to be understood that the supporting structure 50 may be made in any other suitable manner. The supporting structure 52 has insulatedly attached near the free end of the long leg thereof, a plurality of terminals 60 and stationary contacts 62, as previously noted, and has attached at the free end of the short leg thereof one end of the resilient member 56. In addition, a manually operable controlling device 66, such as a set screw, is threadedly engaged with the supporting structure 52, and operatively associated with the main bimetallic member 54 and resilient member 56, at substantially their junction.

The main bimetallic member 54 is substantially a strip-type bimetallic member adapted to flex away from the main or long leg portion of the supporting structure 52 with an increase in temperature thereof. The bimetallic member 54 is rigidly attached to the J-end of the supporting structure 52 by the U-shaped resilient member 56. The resilient member 56 thus tends to bias the cooperative end of the bimetallic member 54 upwardly or towards the main portion of the supporting structure 52 and against the heat-responsive movement of bimetallic member 54 and cooperating manually operable controlling device 66. It, therefore, follows that the man-

ually operable controlling device 66, when rotated clockwise, will force the resilient member 58 and the bimetallic member 54 downwardly to disengage the cooperating movable contacts 64 from the stationary contacts 62, as hereinafter described. If desired, the controlling device 66 may be rotated such a distance that it will force the free end of the bimetallic member 54 downwardly to such an extent that, regardless of the temperature thereof, such bimetallic member 54 will not cause the movable contact 64 to engage the stationary contact 62. With the thermostat operable in such ways, it is apparent that such device may be considered as being a manually operable switching device in addition to having thermally controlled circuit interrupting characteristics.

The second bimetallic member 58 is, in this instance, a strip-type bimetallic member which is rigidly attached to the free end of and extends transversely to, the main bimetallic member 54 by means of a coupling device 68. The coupling device 68 has the top portion thereof, which is in contact with bimetallic member 58, somewhat rounded and is insulatedly attached to the main member 54 to permit the second bimetallic member 58 to be tightly attached thereto, and to be insulated therefrom. The device 68 is insulated from the first member 54 by means of suitable insulating washers 70 and is rigidly attached thereto by being riveted over, as shown at 72.

The second bimetallic member 58 is mounted upon the main bimetallic member 54 in such a manner that it will flex in substantially an opposite direction to that of the main bimetallic member for a given temperature change. In other words, with an increase in temperature, the main bimetallic member 54 will flex downwardly or away from the stationary contacts 62, whereas the second bimetallic member will flex concavely upwardly or towards the stationary contacts 62. This arrangement of the cooperating bimetallic members 54 and 58 causes the contacts to be separated an additional amount upon the disengagement thereof, as in the case of the structure shown in Figs. 1 to 4, inclusive, in response to the main bimetallic member 54, and ensures a positive contact pressure between the movable contacts 64 and stationary contacts 62 upon reengagement, as hereinafter described.

In addition, the mass of the second bimetallic member 58 is substantially less than that of first member 54, as is obvious from inspection, so as to permit the second member to quickly return to its normal curvature upon the disengagement of the contacts and consequent cooling of member 58, to ensure an additional separation of the contacts and to avoid any chattering action thereof.

The stationary contacts 62 are rigidly attached to the supporting structure 52 by means of suitable rivets 74 and are insulated from the supporting structure by means of suitable insulating members 76 and 78. In addition, the contacts are operatively associated with the respective terminals 60 through the cooperation of the common fastening rivets 74. The movable contacts 64 are rigidly and electrically attached to the second bimetallic member 58, preferably by being spot welded thereto near the free ends thereof.

It, therefore, follows that with one of the terminals 60 operatively associated with the circuit to be controlled, (not shown) the current flowing in such terminal will pass through the second

bimetallic member 58 and out through the second terminal 66. Accordingly, it is obvious that the operation of the second bimetallic member 58 will be directly responsive to the passage of current therethrough, whereas the bimetallic member 54, which is heated from a heat-emitting apparatus (not shown) in thermal relation with bimetallic member 58, will determine the relative positions between the movable and stationary contacts 64 and 62.

When operating the modified form of the device embodying my invention, as illustrated by thermostat 60, as shown in Figs. 5 to 9, inclusive, with the cooperative contacts 62 and 64 engaged, substantially as shown in Figs. 6 and 7, the current flowing through the associated circuit (not shown) will pass through the second bimetallic member 58. This passage of current through the bimetallic member 58 will cause such member to arc concavely with respect to the supporting structure 52, as shown in Fig. 9. The resulting curvature of the second bimetallic member 58 causes the movable contacts 64 to be biased against the stationary contact 62 and against either the upward or downward biasing action of the main bimetallic member 54. The contact pressure between the cooperating contacts 62 and 64 will, therefore, be increased.

As the temperature to which the thermostat 30 is responsive increases, the main bimetallic member 54 will flex downwardly while the second member 58 becomes arced, carrying the second bimetallic member 58 therewith, it being understood that both members 54 and 58 may receive heat from an exterior surface. The cooperating contacts 62 and 64 will then be disengaged and separated by a certain distance. The current passing through the second bimetallic member 58 will, therefore, be disrupted, permitting the bimetallic member 58 to return to its normally straight curvature, as shown in Fig. 8, producing an increased separation between the cooperating contacts 62 and 64. It is, therefore, apparent that the main bimetallic member 54 will be required to move upwardly an increased distance, corresponding to the amount of curvature or straightening of the second bimetallic member 58 before effecting the reengagement of the contacts 62 and 64, thereby preventing any fluttering between such cooperating contacts.

It is understood that the temperature at which the contacts 62 and 64 are disengaged or reengaged depends upon the relative position of the manually operable device 66 in cooperation with the upward biasing action of the resilient member 58, which flexibly mounts or attaches the main bimetallic member 54 to the supporting structure 52.

It is, therefore, obvious that the device embodying my invention includes a main bimetallic member adapted to operate said device in response to predetermined temperature conditions in cooperation with a second bimetallic member operatively associated therewith adapted to engage and disengage the contacts in response to the movements of the main bimetallic member to separate the contacts an additional amount after disengagement and to ensure a positive contact pressure between the contacts upon reengagement, and thereafter during engagement.

Various other modifications may be made in the device embodying my invention without departing from the spirit and scope thereof, and I desire, therefore, that only such limitations

shall be placed thereon as are imposed by the prior art and the appended claims.

I claim as my invention:

1. A circuit interrupter comprising, in combination, normally engaging contact means for making and breaking a circuit, a main heat-responsive member and a second heat-responsive member movable in the same direction upon an increase of temperature, means for causing separation of said contact means after a predetermined degree of travel together, said second member thereupon cooling and reversing its direction of movement more quickly than said main member to effect further disengagement of said contact means.

2. A circuit interrupter comprising, in combination, a supporting structure, contact means for making and breaking a circuit, a main heat-responsive member attached at one end to said structure and movable to separate the contact means in response to predetermined temperature changes, and a second heat-responsive member attached at one end to said structure and movable towards contact-making position in response to said temperature changes and also movable to separate the contact means an additional distance upon cooling pursuant to interruption of the circuit in response to movement of said main heat-responsive member.

3. A circuit interrupter comprising, in combination, contact means for making and breaking a circuit, a main heat-responsive member movable to separate the contact means in response to predetermined temperature changes, and a second heat-responsive member movable towards contact-making position in response to said temperature changes and also movable to separate the contact means an additional distance upon cooling pursuant to interruption of the circuit in response to movement of said main heat-responsive member.

4. A circuit interrupter including, in combination, a supporting structure, a mounting frame, means for flexibly attaching said frame to the structure, a plurality of contacts, a main bimetallic member adapted to operate the contacts, and a second bimetallic member attached to said means and operatively associated with the main bimetallic member, said second member adapted to further separate the contacts after disengagement thereof and to insure a positive contact pressure between the contacts.

5. A circuit interrupter including, in combination, a supporting structure, a mounting frame, means for flexibly attaching said frame to the structure, a plurality of contacts, a main bimetallic member adapted to operate the contacts, a second bimetallic member attached to said means and operatively associated with the main bimetallic member to move in the same direction to insure a positive contact pressure between the contacts, means for arresting such movement of said second bimetallic member to effect separation of said contacts, and adjustable means operatively associated with the frame and second member for adjustably limiting movement of the second member.

6. A circuit interrupter including, in combination, a supporting structure, a mounting frame flexibly attached to the structure, a plurality of contacts, a main bimetallic member adapted to operate the contacts, a second bimetallic member attached to the mounting

frame and operatively associated with the main bimetallic member, said second member being snap-acting and adapted to separate the contacts after disengagement thereof and to insure a positive contact pressure between the contacts, and manually adjustable means comprising screws operatively associated with the frame and second member for adjustably limiting movement of the second member.

7. A thermostatic circuit interrupter including, in combination, a supporting structure, a mounting frame flexibly attached to the structure, a main bimetallic member adapted to move in given directions with changes in temperatures thereof to operate the interrupter, a plurality of contacts, one of said contacts being attached to the bimetallic member, a second bimetallic member attached to the mounting frame and operatively associated with the main member and adapted to move in the same directions as those of the main member with corresponding temperatures thereof, a second of the contacts being attached to the second member and operatively associated with the first contact, said second member adapted to further separate the contacts after disengagement thereof and to insure a positive contact pressure between the contacts, adjustable means operatively associated with the frame and second member for adjustably limiting movement of the second member, and a second manually adjustable means operatively associated with the supporting structure and the flexibly mounted frame for adjustably moving the frame and operatively associated second bimetallic member with respect to the first bimetallic member for regulating the operation of the circuit interrupter.

8. In a circuit interrupting device including, in combination, a supporting structure, a main bimetallic member flexibly attached at one end to the structure and adapted to operate said device in response to predetermined temperature conditions, a plurality of contacts including stationary contacts attached to the structure and movable contacts operatively associated therewith, and a second bimetallic member attached at substantially its mid point to the free end of and extending at substantially right angles to the main member adapted partly by the inherent movement of its two ends and partly in response to the movements of the main member to engage and disengage the contacts and further adapted to separate the contacts an additional amount after disengagement.

9. A circuit interrupter adapted to operate an electric circuit, including, in combination, a supporting structure, contact means for making or breaking such circuit, a main bimetallic member attached at one end thereof to the structure for separating the contacts in response to predetermined temperature changes, and a second bimetallic member attached to the free end of and extending at substantially right angles to the main member adapted to be positioned within the circuit, said second bimetallic member being movable towards contact-making position upon an increase in temperature and movable to separate the contact means an additional distance upon cooling pursuant to interruption of the circuit in response to movement of said main heat-responsive member.

PAUL R. LEE.
